METHOD OF MAKING SHEET METAL CONTAINERS

John Haycock, Larchmont, N. Y., assignor to Continental Can Company, Inc., New York, N. Y., a corporation of New York.

Application September 28, 1942, Serial No. 459,983.

1 Claim. (Cl. 113—120)

The invention relates to new and useful improvements in a sheet metal container and more particularly the sheet metal container shown and described in the patent granted I. W. England and John Haycock, September 28, 1943, No. 2,330,207.

An object of the invention is to provide a method of forming the seam for a sheet metal container wherein the edge portions of the body blank are cut in order to shape the edge portions so that they may be abutted and mechanically interlocked, and the cut edges brought into intimate contact with each other, immediately after which the edges are united by solder bonding.

These and other objects will in part be obvious and will in part be more fully hereinafter disclosed.

In the drawing,

Figure 1 is a view of a body blank which has been cut and shaped at the edge portions for forming projections and companion recesses which may be interlocked;

Figure 2 is a side view of a completed can body;

Figure 3 is a detail on an enlarged scale showing the edge portions cut and shaped for interlocking before they are assembled;

Figure 4 is a view similar to Figure 3 but showing the parts assembled ready for bumping;

Figure 5 is a sectional view on the line 5—5 of Figure 4; and

Figure 6 is a view similar to Figure 5 showing the seam bumped and the cut edges of the projections and recesses forced into intimate contact with each other.

The invention as illustrated in the drawing is applied to the forming of a side seam of a sheet metal can body. The completed can body is indicated at 1 in Figure 2, and the side seam joining the edges thereof is indicated at 2. The can body is made from a blank of sheet metal indicated at 3 in Figure 1 of the drawing. The edge portion 4 of the blank is cut so as to provide a series of spaced projections 5, 5. Between the projecting portions are spaced recesses 6, 6. The other edge 7 of the blank is cut so as to provide spaced projecting portions 8, 8 between which are recesses 9, 9.

The projecting portions 5, 5 are wider at their outer ends than their neck portion 5a which supports the projection. As shown in the drawing, the sides and end of each projection are straight walls meeting at angles. It is obvious that these projecting portions may be otherwise

shaped, but it is essential that the outer free end portion of each projection shall be wider in a direction longitudinal of the seam than the neck portion of the projection which supports the seam. The projections 5 are dimensioned so that when the seam is completed each projection will completely fill and make abutted contact with the edges of the companion recess 9. The projection 8 is shaped and disposed so that it will completely fill and make edge contact with the edges of the companion recesses 6 between the projections 5, 5. The projecting portions 5 are initially curved along a line x—x which extends longitudinally of the seam. This draws the side edge 5b nearer to the side edge 5c and greatly facilitates the placing of the projections 5 in their corresponding recesses 9.

In the making of the can body the blank is cut and shaped at its side edge portions to form the seam, and immediately thereafter the edge portions are brought together and the projections interlocked with the recesses as shown in Figures 4 and 5. Then the side seam is subjected to a bumping operation of the usual character. This bumping operation consists in the placing of the interlocked edge portions on a bumping anvil or horn and the striking of the same with a bumping iron which is shaped to conform to the curvature of the body so that when the side seam is bumped the cut edges of the projections and the recesses will be brought into intimate contact, thus producing a mechanical interlock between the edge portions of the can body. Furthermore, the curved plane of the interlocked portions will conform to the cylindrical curvature of the body.

The interlocked portions first described do not extend the complete length of the side seam but at each end of the side seam the blanks are so shaped as to overlap, as clearly shown in Figures 3 to 6. In Figure 3 the outer lapping portion at the upper end of the seam is indicated at 10 and the inner lapping portion at 11. When the seam is bumped, these lapping portions are curved and brought into close contact with each other. The bumping of the seam causes the projecting portions which are initially curved to straighten out and make very tight intimate contact with the edge portions of the recess in which they are disposed. This will firmly hold the edges of the blank interlocked and the lapped portions in contact preparatory to solder bonding the side seam. Immediately after the bumping of the side seam the can body is passed through the soldering mechanism and solder applied to the

side seam for solder bonding the interlocked portions and lapped portions thereof.

It will be noted that the blank is cut so as to provide these interlocking mechanical parts, and immediately the parts are brought together and interlocked. This cutting leaves a clean-cut edge and the parts are brought together and interlocked and the seam bumped before the cut edges will oxidize and produce objectionable scale which interferes with the solder bonding operation. Furthermore, as soon as the seam is bumped it is at once soldered so that the clean intimately contacting metal surfaces will cause the solder applied to the seam to flow by capillary attraction in between the parts and join the metal parts into a substantially integral structure.

It is further noted that in the finished side seam the mechanically interlocked parts all lie in the curved body of the container and therefore the container may be very readily lacquered or coated with wax or any other desired non-metallic coating, both inside and outside, and a uniform thickness of coating obtained. When the can body is made up in the manner described above, the ends of the body are flanged in the usual way and a bottom end 12 is secured thereto by double seaming. After filling, a top end 14 may be seamed to the body in the usual way.

I claim:

The method of making a side seam for a sheet metal can body comprising cutting one edge of the body blank so as to provide spaced projecting portions along the edge of the blank which projecting portions are wider at the free ends thereof than at the portion joining the body blank, cutting the other edge of the body blank so as to provide recesses spaced the same as the projections, all edges of the projections and recesses being cut edges, said projections and recesses being shaped so that when the projections are inserted in the recesses the edges of the projections will make intimate contact with the edges of the recesses, curving the projecting portions transversely of the center line thereof so as to reduce the over-all area of the projections to facilitate the insertion of the same in the respective recesses of the other edge portion of the blank placing said curved portions while the edges are freshly cut and free from oxidation in said recesses, bumping the seam so as to straighten out the curvature of the projecting portions and bring said cut edges thereof into intimate contact with the cut edges of the recesses and immediately metal bonding the side seams for hermetically uniting the contacting edges.

JOHN HAYCOCK.
